(57) **CLAIM**

The ornamental design for a vehicular steering wheel, as shown and described.

DESCRIPTION

FIG. 1 is a front perspective view of a vehicular steering wheel showing our new design;

FIG. 2 is a front elevational view thereof;

FIG. 3 is a top perspective view thereof;

FIG. 4 is a side elevational view thereof;

FIG. 5 is an opposite side elevational view thereof;

FIG. 6 is a bottom perspective view thereof; and,

FIG. 7 is a rear elevational view thereof.

The broken lines shown representing the "LUCID" text, front attachment features and tilt adjustment features throughout the drawing views are for environmental and illustrative purposes and from no part of the claimed design.
